WILLIAM JOSEPH WILLETT BRUCE, OF WALLASEY, ENGLAND

VALVULAR APPARATUS

Application filed October 11, 1928, Serial No. 311,920, and in Great Britain November 10, 1927.

This invention has reference to valvular apparatus for controlling the flow or supply of steam or other gaseous fluids to apparatus wherein it is used, or the release of such fluids. For instance the apparatus can be used for controlling the supply of steam from steam generators on board ship to other apparatus thereon, or to the relief or release of steam from the generators into the atmosphere or otherwise as required or to steam whistles or sirens or the supply of compressed air to whistles, and the like; and the type of the apparatus is that in which a pilot valve serves to control the admission of steam or other fluid from the source of supply into a cylinder or chamber containing a piston or equivalent movable device connected with the main controlling or supply valve on the supply pipe, for the purpose of opening it.

The pilot valve, which is relatively small, is actuated by hand or mechanically, or it may be operated automatically by pressure of steam or other fluid.

Amongst other things, the object and effect of the present invention is to provide improvements in valvular apparatus of the kind concerned by which they are rendered more simple and reliable, and are capable of being examined and repaired readily, and also manufactured cheaply.

In apparatus according to this invention the pilot valve casing—which is made separately from the main valve casing—is carried from and mounted on a flange, or an extension of a flange at one end of the main valve case, and so the flange serves as a pedestal to the pilot valve case, to which it may be fixed by suitable studs or bolts.

The pilot valve proper operates in connection with a small hole or port beneath it in the flange or pedestal, and the steam or other fluid is admitted to the case of this valve—which is proved by the bottom portion of the casing of the pilot valve—through a port leading out of the interior of the main valve case, it will act on the small valve tending to press it down, and also on the piston or larger part above it, which tends to move it in the opposite way; and when the pilot valve is

lifted, fluid will pass through the port normally controlled by the valve, and a port in the pedestal, whence it is conducted by a part on the valve casing to the cylinder connected with the main valve and so fluid is supplied into the interior thereof, and acts on the piston or its equivalent, and opens the valve.

A spring exists between the upper end of the valve case and the piston or guide part, and normally presses pilot valve proper on to the seat surrounding the delivery steam aperture.

By this construction a small chamber is provided at the lower end of the pilot valve casing, to which as stated steam from the main inlet branch of the main valve normally has access.

In the case of the apparatus being used as an automatic steam generator or pressure relief valve, the end of the piston cylinder to which steam is conducted through the action of the pilot valve described, is in communication with the interior of the casing of the water discharge valve, by means of a port between these parts, so that water falling to the bottom of this end of the cylinder, can flow away by the port or hole into the valve case, and it is kept free of water, so avoiding "water hammer".

In cases when the apparatus is to be used where there is possibility of accumulation of water, say in a pipe connecting the inlet of the valve with the steam generator, the valve is adapted to allow of the release of such water and this is accomplished by forming a communication between the interior of the steam inlet of the valve case, and the inner or upper chamber of the condensed water release valve as above described.

When the valvular apparatus is used in a case where the discharge side of the main valve is not liable to be filled with water, or is normally filled, the automatic non-return valve for the escape of water (which is used when the apparatus is required for whistle control or the like) is dispensed with and in such a case to carry off water of condensation in the supply side of the valve, and prevent "water hammer", a hole or conduit is provided on the inlet branch of the main valve

which leads to an independent or separate drain trap or other outlet.

The drawings illustrating the invention are annexed, in which Figure 1 is a plan in part section; Figure 2 is an end view; Figure 3 is an elevation showing the hand operated pilot valve and ports in section; and Figure 4 is a section showing a detail.

In the drawings, 1 designates generally the main casing of the valve; 2 is the valve seat within the casing; 3 is the main valve; 4 is the valve stem or rod; 5 is the piston; 6 the cylinder in which it works; and 7 generally designates the pilot valve.

It may be assumed that the valve shown in the drawing is adopted to control the supply of steam or other gaseous fluid to any apparatus where periodical flow or supply is required, such for instance as a whistle or siren, the pilot valve being adapted to be operated and controlled by hand, in the case shown by a hand operated lever 8, which is actuated, say manually, whenever a supply of steam or other fluid is required to be delivered to the place of use.

Of the pilot valve 7, 9 is the valve proper, which controls the supply of steam or other fluid to the cylinder 6 for operating the piston 5, and opening the main supply valve 3; and this steam or fluid is led from the interior of the supply inlet branch 17 of the valve case 1 below the valve 3, to the top of the valve 9 by a port 10, and a short vertical port 11, leading directly into the valve chamber proper 14, the ports 10, 11 being formed—say by drilling—in the bottom flange 12 of the main valve. This flange 12 is made especially thick and is extended outwards radially where the valve 7 comes, and forms a support or bed for same upon which its flange 13 rests, it making joint with the upper surface of the flange 12 by means of studs or bolts.

When the valve 9 is opened the fluid enters the valve chamber 14, and passes down a vertical port 15, and horizontal port 16, and thence by another vertical port 15^x to the cylinder 6, the piston 5 of which when this happens will be moved, and the valve 3 opened allowing steam or other gaseous fluid to pass through the apparatus.

The ports 15 15^x and 16 are similarly formed to the port 10 by drilling holes in the flange 12; namely, the vertical port 15 is drilled downwards from the face on which the valve 9 rests, the port 16 is drilled from the outside of the flange 12 in a horizontal direction, whilst the other vertical port 15^x is drilled from the bottom of the flange 12 vertically up through a projecting part 17^x on the steam supply branch 17 of the main steam valve. The outer ends of these ports 16 and 15^x are plugged or welded after drilling and so closed.

The valve 9 has above it a portion consist-

ing of a piston 18, which fits and works within an inwardly projecting portion 19 of the casing 20; and on the lower part of this piston part 18, are two enlarged parts 21 and 22, the former of which works in an annular recess in the part 19 as shown, whilst the larger part 22 operates in connection with the under surface of the part 19, so that these parts form a sliding closure between the valve chamber 14, and the upper part of the casing 20, and prevent the escape of fluid past it; while the valve is normally pressed upwards by the pressure, but it is kept upon its seat by a spring 23 in the casing 20, the bottom of which rests on the piston part 18, and the top on the bottom of a gland collar 24, which screws into the top of the casing 20, and according to the degree it is screwed in, so will be the pressure exerted by the spring 23 on the valve.

The valve parts 9, 18 are connected to the operating lever 8 by a stem 25, which passes through the neck 24, and its upper end is secured to the end of the lever.

In the case where steam is the fluid used, a drain valve of the kind hereafter specified is provided on the valve case, and communicates with the space of the valve case proper beneath the main valve 3, and the cylinder 6 for carrying off any water that may be formed in or find their way into these parts.

The pilot valve 7 is disposed in relation to the inlet and discharge branches of the main valve at a point lying between the general vertical and transverse planes of the valve apparatus as a whole, so that it lies nearer to the end of the cylinder 6 than to the opposite end of the valve case. By so arranging and disposing this valve, the formation of the ports in the flange 12 is facilitated, and the valve is as a whole rendered more compact; and the part 17^x on the outside of the branch 17, to be used for having the port 15^x formed on it.

The hand operating lever is supported by a pivot stud 26, which screws into a boss 27 formed on the side of the valve casing 1 as shown in dotted lines in Figure 1.

In the case of the fluid being steam, to prevent water of condensation getting access to the cylinder 6 and piston 5, from the interior of the valve case, a spring sealing device 28 is used between a shoulder on the valve stem 4—as shown—and the end of the cylinder through which this steam passes; and in the case shown this sealing device is in the form of an annular plate spring round the rod 4—which is normally under stress—resting on the shoulder on the stem and bearing at its edge on the surface of the cylinder closed end. Thus a metallic closure exists between the valve stem and the end of the cylinder.

It will be seen that by the construction of apparatus described, when it is desired to inspect or open the cylinder 6, no pipe or other

connection, other than the removal and replacement of the cylinder cover 29, will have to be made or unmade.

In cases where the valve is used to control the supply of steam to apparatus say on a ship, such as a steam whistle or siren, and water is liable to collect in the discharge part of the valve and pipe above it, which leads to the whistle or apparatus, a hole is provided leading to a chamber below (obliquely arranged in the valve casing) within which is a valve, normally kept open by a spring, so that as the water of condensation reaches the casing it can pass away by a pipe or drain; whereas if the main valve is opened, the steam under pressure exists in the discharge side of the drain valve case, then this pressure acting upon the head of the valve will press it down against the action of the spring, and close it, and no steam can escape.

This valve is shown in Figure 4 in section, 30 being the valve proper, working in connection with the seat 31 of the valve case; and 32 is the spring by which it is normally kept open, while 33 is a chamber or space above the valve. 34 is a port leading from the steam delivery space beneath the valve 30 by which any water collecting in this portion of the valve case can pass away through this port into the chamber 33, and then past the valve 30 it being carried away from the valve case by the drain branch 35, and a suitable drain pipe.

The hole or port which connects the outer end of the cylinder 6 with the chamber 33 of the valve 30 is marked 36 and by it water is automatically drained away from the cylinder.

With regard to cases in which the apparatus on the discharge side of the valve 3 is not liable to become filled with water, but where it is connected with a steam generator, the valve 30 may be dispensed with, and to carry off any water in the steam inlet branch (17) to the main valve, a hole 37 shown in dotted lines will be formed in the valve casing, so that water from this branch can pass away through this opening, which will be connected by a drain pipe and steam trap. By this means "water hammer" in the apparatus is prevented.

If the apparatus is to be used as an automatic pressure relief valve, the pilot valve and ports connected with it would be so adapted that the pilot valve proper 9 would be lifted off its seat by the steam at a predetermined pressure, and so it would pass to the cylinder 6, and open the main valve 3, and release the steam or fluid.

What is claimed is:—

1. A valvular apparatus including a pilot valve which controls the supply of fluid to the cylinder and piston connected with the main valve for operating the same, said pilot valve being supported on a flange of one of

the branches of the valve case through which the fluid passes, the lower part of the casing of the pilot valve, which is open below, resting on an extended part of one of the flanges of the apparatus, and the pilot valve proper operating on a seat on the surface of the flange, and in a chamber formed by the lower part of the valve casing, and steam or fluid being normally supplied from the interior of the main valve casing; a closure between the lower pilot valve chamber, and the upper part of the casing thereof being effected by a sliding piston type of fitting.

2. A self-contained valvular apparatus comprising a main valve for controlling the supply of fluid to the article or part to be operated and a piston and cylinder contained axially in line, inlet and outlet branches with attaching flanges, the axes of which are transversely disposed in relation to the axis of the main valve and its cylinder and a pilot supply control valve one end of the case of which is attached to the outer surface of one of the said flanges of the inlet or outlet branches of the main valve case.

3. Apparatus for controlling the supply of fluid as defined in claim 2, wherein ports between the pilot valve chamber proper, and the interior of the main valve casing passages through which the fluid passes, are formed by holes, partly in the flange supporting the pilot valve case, and partly in the metal of the main casing of the apparatus.

In testimony whereof I have subscribed my name to this specification.
